UNITED STATES PATENT OFFICE.

ELIAS B. QUICK, OF BROOKLYN, NEW YORK.

CEREMONIAL GONG.

SPECIFICATION forming part of Letters Patent No. 556,208, dated March 10, 1896.

Application filed November 1, 1894. Serial No. 527,650. (No model.)

To all whom it may concern:

Be it known that I, ELIAS B. QUICK, a citizen of the United States, residing at Brooklyn, in the county of Kings and State of New York, have invented new and useful Improvements in Gong-Boxes and Striking Mechanism, of which the following is a specification.

This invention has for its object to provide 10 a novel, simple, and effective gong-box and striking mechanism particularly designed for secret and other societies for the purpose of indicating a certain hour or producing musical sounds during ceremonies.

15 The invention also has for its object to avoid the use of spur-gearing in gong-striking mechanism, and to provide novel means whereby the tone of the instrument is improved and the discord incident to the whizzing of gear-wheels is entirely avoided.

20 To accomplish these objects my invention consists essentially in the combination of a casing, a sounding-box located within the casing and having a sound-inlet opening and 25 a sound-exit opening, a gong arranged above the sound-inlet opening of the sounding-box, so that the sound is delivered through the sound-inlet opening into said box, a gong-striker, a rotary handle arranged outside the 30 casing, and devices located within the casing and actuated by the rotary handle for operating the gong-striker.

The invention also consists in the combination 35 of a casing, a sounding-box arranged within the casing and having a sound-inlet opening and a sound-exit opening, a gong arranged in juxtaposition to the sound conductor or conveyer so that the sound of the gong is delivered into the sounding-box, a 40 rock-shaft having a crank-arm and a rod provided with a striker, a spring serving to turn the rock-shaft in one direction, a rotary shaft having a handle arranged outside the casing, and a cam arranged on the rotary shaft inside the casing and acting on the crank-arm of the rock-shaft to turn the latter in the opposite direction, whereby a vibratory motion is imparted to the gong-striker.

45 My invention also consists of a sounding-box provided with a sound-outlet and having a sound-board in combination with a stand-

ard connected with the sounding-box and a gong carried by said standard.

50 My invention also consists in the novel features of construction and combination of parts hereinafter fully set forth and claimed.

The invention is illustrated by the accompanying drawings, in which—

55 Figure 1 is a vertical sectional view of a gong-box and striking mechanism constructed in accordance with my invention. Fig. 2 is a vertical sectional view taken on the line 22, Fig. 1, looking in the direction of the arrow; and Fig. 3 is a detail perspective view of a portion of the striking mechanism. 65

In order to enable those skilled in the art to make and use my invention I will now describe the same in detail, referring to the drawings, wherein it will be seen that the casing is composed of a base-piece, 1, side 60 walls, 2, end walls, 3, and a top piece, 4, constructed to provide a closed structure, except as to sound-exit orifices 5 in one of the walls, preferably in one of the end walls. 70

The bottom piece is provided on its inside 75 with blocks 6 supporting a hollow sounding-box 7 having a solid end portion 8 secured to the blocks through the medium of screws 9 and upper and lower sound-boards, as shown. The solid end of the sounding-box supports 80 a post or standard 10, confined at its lower end by a screw-nut 12 or otherwise, and having at its upper end a disk or plate 13, to which a ring 14 is attached by screw 15. The ring and screw serve to hold one end of a gong 85 16 composed of a volute or spiral scroll wire of spring-steel. This form of gong is preferred; but I do not limit myself to any specific construction of gong or bell.

The upper portion of one of the end walls, 90 3, is provided with attached bearing-blocks 17, in which are mounted the extremities of a rock-shaft 18 having a crank-arm 19 and a striker-carrying arm 20. The arm 20 is secured at one end to the rock-shaft, and is provided at its other end with a hammer or striker 21, preferably secured in position on the rod by a screw 22, whereby the hammer or striker is susceptible of adjustment along the length of the rod to vary the tone of the 100 gong if the latter is constructed of a volute or spiral scroll wire. The rock-shaft 18 is also

provided with an arm 23, against which bears one extremity of a leaf-spring 24, secured at its other extremity to a fixed block 25 by means of screws 26. The block 25 is rigidly 5 supported in the casing and the leaf-spring acts upon the arm 23 with a tendency to turn the rock-shaft in such direction as will force the hammer or striker 21 toward the gong 16.

In the top portion of the casing is arranged 10 a sleeve 27 having at one end a flange 28 by which it is rigidly secured to one of the side walls, 2, through the medium of screws, as at 28. The side wall to which the sleeve is secured is provided with an opening 29, coincident with the sleeve, and through the opening 29 extends the angular end 30 of a rotary shaft 31, arranged within the sleeve and having at its inner end a duplex cam or tappet 32. The angular end 30 of the rotary shaft is 15 adapted to receive a crank-handle 33, by which the shaft can be turned for the purpose of causing the cam or tappet 32 to lift the crank-arm 19 and thereby raise the striker-carrying arm 20 in an upward direction against the 20 tension of the spring 24.

When the cam or tappet projections of the rotary shaft pass from engagement with the crank-arm 19, the spring 24 suddenly throws the striker-carrying arm 20 in a downward direction and causes the striker 21 to sound the gong. The sound of the gong is conveyed or 25 conducted into the interior of the sounding-box 7 through the medium of a funnel-shaped inlet-opening or sound conductor or conveyer 30 34, supported by the sounding-box and having its receiving-mouth arranged in juxtaposition to the gong. The upper wall of the sounding-box is provided with a sound-escape opening 35, one or more, and thus the sound 30 is delivered into the interior of the casing, from which the sound escapes through the sound-exit orifices 5.

The sounding-box acts similar to a sounding-board and improves the tone of the gong 45 while amplifying the sound for the purpose of producing a very effective instrument.

As before stated, the instrument is designed particularly for sounding a certain hour or producing musical sounds during the ceremonies of secret or other societies; but obviously the invention can be used for any purpose for which it is adapted.

The duplex construction of the cam or tappet 32 secures two strokes of the hammer or 50 striker for every revolution of the shaft 31.

The handle 33 is designed to be removed and replaced, and is preferably in the form of a crank to facilitate the rotation of the shaft

31; but I do not confine myself to any particular form of handle. 60

The invention entirely avoids the presence of spur-gearing in gong-striking mechanism, which is very desirable for the purpose in hand, in that the discord incident to the whizzing of gear-wheels is avoided and harmonious musical sounds are produced by a gong 65 by very simplified devices.

Having thus described my invention, what I claim is—

1. The combination of a casing, a sounding-box arranged within the casing and provided with a sound-inlet and a sound-exit for conveying the sound into and out of said box, a rock-shaft having a crank-arm and a rod provided with a striker, a spring which 70 operates to turn the rock-shaft in one direction to throw the striker against the gong, a rotary shaft having a handle outside the casing, and a cam mounted on the said rotary shaft inside the casing and acting on the 75 crank-arm of the rock-shaft to turn the latter and lift the striker against the tension of the spring, substantially as described.

2. The combination of a casing, a sounding-box arranged within the casing and provided with a funnel-shaped sound-inlet and a sound-exit for conveying the sound into and out of the box, a gong arranged over the funnel-shaped sound-inlet, a rock-shaft having a crank-arm and a rod provided with a striker, 80 a spring acting to turn the rock-shaft in one direction to throw the striker against the gong, a rotary shaft having a handle arranged outside the casing, and a cam mounted on said 85 rotary shaft and acting on the crank-arm of the rock-shaft to turn the latter against the tension of the said spring, substantially as described.

3. In a gong, a sounding-box provided with a sound-outlet and having a sound-board, in 100 combination with a standard connected with the sounding-box and a gong carried by said standard, substantially as described.

4. In a gong, a sounding-box provided with a sound-outlet and having a sound-board, in 105 combination with a standard connected with the sounding-box, a disk carried by said standard, and a gong carried by said disk, substantially as described.

In testimony whereof I have hereunto set 110 my hand in presence of two subscribing witnesses.

ELIAS B. QUICK.
